BED ELEVATOR

Frank G. Lang, Miami, Fla.

Application December 13, 1948, Serial No. 65,049

3 Claims. (Cl. 5—11)

1

This invention relates to improvements in bed elevators and has particular reference to elevators for increasing the height or angularity of conventional beds.

It is an object of the present invention to provide an elevator for detachable connection to the legs of beds and having means for adjusting and holding the device and its attached bed post in various degrees of elevation for converting the conventional home bed into a hospital bed.

A further object of the invention contemplates a bed elevator that is detachably clamped to the four legs of a bed, either round or square, with adjustable means in the elevator whereby the bed may be elevated to a desired height or inclined from either end as may be desirable.

Another object of the invention resides in the particular features of novelty and simplicity that permit quick and easy attachment to the posts or legs of a bed without the use of tools or other implements, is easily adjustable within a wide range, will securely hold the bed against accidental dropping, is designed for both the right and left side of the bed, is strong, durable, light in weight, cheap to manufacture, is ornamental in appearance and highly convenient in use.

Other important objects and advantages of the invention will readily present themselves during the course of the following description, reference being had to the accompanying drawings, wherein is shown a preferred embodiment of the invention.

In the drawings:

Figure 1 is a side elevation of a bed illustrating the invention in use.

Figure 2 is a section on line 2—2 of Figure 1, with the elevator in elevation.

Figure 3 is a horizontal section taken on line 3—3 of Figure 1.

Figure 4 is a side elevation of the device, taken at a right angle to the illustration of Figure 1.

Figure 5 is a vertical section taken on line 5—5 of Figure 3, and

Figure 6 is a vertical section taken on line 6—6 of Figure 5.

Like numerals are employed to designate like parts throughout the several figures of the drawings.

Referring specifically to the drawings, the numeral 5 designates the invention as a whole and, as shown in Figure 1 is attached to the legs 6, of a bed, generally indicated at 7. The legs 6 may either be round or square, since the invention readily adapts itself to either form. It is contemplated that an elevator be attached to all four

2

legs of the bed, although elevators may be attached to either the front or back legs whenever it is desired to merely adjust the bed to an incline. The elevators are adapted to be formed in rights and lefts.

Each elevator comprises a supporting standard 8, preferably square in cross-section and of a desirable height to permit elevation of the bed within recognized limits for convenient manipulation of a patient in the bed. The standard 8 is preferably provided with a caster 9 at its lower end for convenience in shifting the bed around after elevation. One vertical face of the standard 8 is provided with ratchet teeth 10 extending entirely thereacross, for a purpose to be described. A stop lug 11 is fixed to the standard adjacent its upper end for limiting the upper movement of a carriage, to be described.

A carriage 12 is adapted to traverse the standard, carrying with it, the legs 6 of the bed. Each carriage 12 comprises a rigid frame, embodying vertically arranged walls 13 and 14, integral and positioned at a right angle with respect to each other for forming a vertically arranged L-shaped

socket for engaging over the leg of the bed. The walls 13 and 14 are reinforced at top and bottom by flanges 15 and 16. The upper and lower flanges 15 and 16 jointly are extended outwardly and provided with aligned square openings 17 for the slidable reception of the standard 8. The lower flanges 15 and 16 are extended inwardly to jointly form a supporting rest 18 for the terminal end of the bed leg.

Since the conventional bed leg is provided with a bead or other enlargement at its lower end for ornamental purposes, it follows, that means must be provided to maintain the leg 6 in perfect alignment with the carriage. To provide for this contingency, the upper flanges 15 and 16 are extended slightly inwardly, as indicated at

19 for aligning abutment with the side of the bed leg. Additional aligning means, in the form of ribs 20 and 21 may likewise be cast integral with the carriage frame 12 to insure greater rigidity of the leg 6, when in clamped position. The rest 18 is preferably cut away, at 22 for accommodation and clearance of such casters as may be carried by the leg 6.

It will thus be seen, that the carriage 12 will partially embrace the leg 6 in perfect vertical alignment with the weight of the bed supported on the rest 18.

Means are provided to securely clamp the carriage in position upon the leg 6 and this means comprises an integral horizontal and lateral extension 22' of the carriage 12, having an inwardly turned hooked and bifurcated end 23. Pivotally

supported at 24 in the bifurcated end 23, is a latch member 25, having a hooked latch end 26 and a finger engaging end 27. A compression spring 28 bears between the inner end of the bifurcation and the end 27 for normally retaining the latch in operative position. The extension 22 is positioned substantially intermediate the ends of the carriage. An arcuate clamp 29 is pivotally supported for horizontal swinging movement in a pair of spaced ears 30, extending from and integral with the side wall 14 of the frame, by a pivot pin 31. The clamp 29 is arranged in horizontal alignment with the latch 25 and the free end of the clamp 29 is hooked, as at 32, for detachable engagement with the latch end 26. The clamp 29 is provided with a cylindrical enlargement 33, provided with a horizontal threaded opening 34 for the threaded reception of a screw device 35. The screw 35 is provided with an operating wing end 36, outwardly of the clamp 29, while the inner free end of the screw is provided with a swivelled cushioned clamping end 37, for engagement with the side of the leg 6, in operative position.

It obviously becomes necessary, since the carriage is adapted to traverse the standard 8, that means be provided to retain the carriage and its associated leg 6 in vertical elevation. To provide for this contingency, a pawl 38 is pivotally supported at 39 in a recess 40 of the extension 22 for horizontal swinging movement toward and from the ratchet teeth 10 of the standard. A U-shaped spring 41 has its free ends anchored in openings formed in the body of the extension 22 and bears against the pawl 38 for normally urging the same constantly toward the standard. A finger release lip 42 is formed on the pawl for convenience in disengagement of the pawl when it is desired to lower the carriage 12 on the standard.

In the use of the elevator, the carriage is moved to its lowermost position on the standard, in which position, the rest 18 can be engaged beneath the lower end of the leg 6. The clamp 29 having first been swung to open position, indicated by dotted lines in Figure 3, is now swung inwardly until its end engages the spring pressed latch 25. The screw 35 is then adjusted until its cushion end firmly clamps the leg 6 against the flanges 19 and ribs 20 and 21, at which time the leg 6 is securely held against movement with respect to the carriage. The operator then manually lifts the corner of the bed to the required height, carrying with it the carriage, which slides upon the standard 8. During the vertical adjustment, the pawl 38 rides over the teeth 10 and automatically engages a selected tooth for preventing a downward movement of the carriage. The operator then proceeds to adjust the height of the remaining corners of the bed. When it is desired to return the bed to its normal position, the pawl is disengaged, permitting the weight of the bed to carry the carriage downwardly to a position where the leg 6 rests upon the floor. The screw may then be released and the clamp 29 disengaged by releasing the latch 25, at which time the elevator may be removed. With the elevators on all four legs 6, the bed can be angularly arranged, by merely lifting one end higher than the other, providing for a proper positioning of a patient as may be desired. After the device is clamped upon the legs 6, it only becomes necessary to lift the ends of the bed to the desired height, causing the carriage to slide upward on the standard 8, where it is held against slipping by the pawl 25.

It will be seen from the foregoing that a very desirable and efficient means has been provided supporting a bed in elevated position, as is necessary in the handling of sick persons. The device is extremely simple and easy to attach and will maintain the bed in elevated or inclined position indefinitely, yet permitting the bed to be shifted around, since the elevators are rigid with the legs 6 through the medium of the clamps 29. The device readily converts a conventional bed into a hospital bed by the addition of the elevators and at a fraction of the cost of the conventional hospital bed. The elevators are preferably cast from a suitably strong metal, finished in ornamental fashion and are made in right and left hand models in order to position the clamp 29 and its clamping screw 35 inwardly so as to avoid any undesirable projections likely to catch upon an attendant's clothing.

20 It is to be understood, that the invention is not limited to the precise arrangement shown, but that it includes within its purview, whatever changes fairly come within either the terms or the spirit of the appended claims.

25 Having described my invention, what I claim is:

1. A bed elevator for use upon the legs of a bed comprising a rigid standard having ratchet teeth formed on one side, a carriage adapted to traverse the standard, guide means on the carriage whereby the carriage is caused to traverse the standard against lateral movement, a pawl pivotally supported on the carriage and adapted to engage the teeth of the standard, spring means for urging the pawl in engagement with the teeth, a clamp pivotally supported on the carriage for horizontal swinging movement, latch means for holding the clamp against movement, said carriage provided with a rest for the bottom of the legs, said clamp adapted to rigidly retain the leg upon the rest and against the carriage and adjustable means carried by the clamp for engagement with the leg of the bed.

2. A bed elevator of the character described for detachable connection with the legs of a bed comprising a non-circular rigid standard having teeth formed on one side for the major portion of its length, an anti-friction caster carried by the lower end of the standard, an elongated generally L-shaped carriage adapted to traverse the standard, guides formed upon the carriage at top and bottom for slidable engagement with the standard, a rest formed upon the carriage at its lower end for the support of a bed leg, an arcuate clamp pivotally supported on the carriage intermediate the top and bottom for swinging in a horizontal plane, said clamp adapted to embrace the said leg, a latch pivotally supported on the carriage for detachable engagement with the clamp, a spring to urge the latch to latching position, a screw device carried by the clamp for engagement with the side of the leg in clamping position, a resilient bumper carried by the contacting end of the screw, a pawl pivotally supported from the carriage for engagement with the teeth of the standard and a spring for urging the pawl to operative position.

3. A bed elevator of the character described for detachable connection to bed legs comprising an elongated standard square in cross-section and provided with ratchet teeth upon one side for the full width of the side, an antifriction roller carried by the lower end of the standard, a stop device carried at the upper end of the standard, 70 a bed leg carriage for detachable and supporting

connection to the leg of a bed, said carriage provided with aligned and square openings for slideable engagement over the standard, said carriage comprising a pair of integral side walls arranged at an angle of ninety degrees with each other, reinforcing flanges formed on the upper and lower ends of the walls, the flanges of the lower end being extended inwardly to provide a rest for supporting the end of the bed leg, ribs formed on the inner side of one wall for the vertical alignment of the bed leg, said walls jointly forming an angular socket for the reception of the bed leg, a pair of spaced ears formed on one wall, an arcuate clamp pivotally supported between the ears for swinging in a horizontal plane, said clamp arranged equidistantly spaced from the upper and lower ends of the carriage, the clamp having a hooked end, a clamping screw threaded through the clamp in a horizontal manner and provided with a cushion bumper on its inner end, a hooked bifurcated extension formed on the carriage, a

latch pivotally supported in the bifurcated end, a spring for urging the latch to operative position in alignment with the hooked end of the clamp, a pawl vertically arranged and pivoted in the extension for swinging engagement with the teeth of the standard, a spring anchored in the extension and bearing against the pawl, said pawl held in slideable contact with the teeth of the standard throughout the upward sliding movement of the carriage.
